United States Patent Office

Des. 196,379
Patented Sept. 24, 1963

196,379

CASSEROLE

Manuel S. Ziskin, Mayfield Heights, and Harold O. Wagner, Sheffield Lake, Ohio, assignors to Kromex Corporation, Cleveland, Ohio, a corporation of Ohio

Filed Jan. 10, 1963, Ser. No. 73,139

Term of patent 14 years

(Cl. D44—15)

Fig. 1

Fig. 2

Fig. 3

FIG. 1 is a perspective view of a casserole showing our new design;

FIG. 2 is a top plan view; and

FIG. 3 is a fragmentary side elevational view thereof.

The essential features of the design are shown in full lines.

We claim:

The ornamental design for a casserole, substantially as shown and described.
